UNITED STATES PATENT OFFICE

ISIDRO MERCIER Y SOLÉ, OF BARCELONA, SPAIN

BOX LOOM

Application filed December 20, 1929, Serial No. 415,586, and in Spain March 1, 1929.

In box looms designed for weaving with various shuttles, owing to the vibration of the looms and the movement of the slay batten, the shuttles that are not working move in their respective boxes and this hinders the working of the looms because when one of these displaced shuttles has to come into action it does not receive sufficient impulse from the picker and at times when the displacement has been considerable this interferes with the movement of the boxes. Generally the boxes have box swells but they do not exert a sufficient pressure on the shuttles when they are not working to prevent their displacement and to avoid the inconveniences above referred to.

The improvement, object of this patent, completely avoids all the inconveniences mentioned above, fixing the shuttles in the interior of their respective boxes while they are not working.

This improvement essentially consists in providing in each of the shuttle boxes a spring or elastic retaining piece which, due to its own elasticity, leaves the shuttle completely free when the box is brought into the working position and, on the contrary, when the box is not working the spring or retaining piece bears against the shuttle over the greater length of the same so preventing its displacement.

For the purpose of the mechanism, each of these springs has an arm that passes through the rear wall of the shuttle box, protruding from the same, and in combination with this arm a guide plate is fixed to the upright of the batten, this latter having such a form as to press all the arms of all the boxes with the exception of that which is in the working position.

In the attached plan all the parts of a box loom are shown, to which the improvement, the object of this patent, has been applied.

Figure 1 is a view seen from above of one end of the batten, the loom boxes being shown partially in section as indicated by the line I—I of Figure 2. Figure 2 is a vertical section taken through the line II—II of Figure 1. Figure 3 is a detail of the boxes seen from above. Figure 4 is a view in perspec-

tive, in small scale, of the retaining spring of the shuttle.

The loom is generally composed of a batten —1— with its verticals —2— and a set of boxes —3— that slide on the guides —4— moved by a convenient mechanism. These boxes have the usual device in looms and each of them is provided, as is also usual, with the corresponding box swell.

This improvement, constituting the object of this application, consists in applying to each of the boxes a retaining device which in the example represented in the figures is composed of a long spring —6— which occupies nearly the entire length of the shuttle box. These springs are strips of steel designed with a longitudinal aperture —16— in order to allow the entrance of the box swell —5— and they have one extreme bent forming an arm —7— that passes through an orifice made in the rear wall of the shuttle box coming out at the rear part of the box.

In combination with these springs —6— a support —9— is provided fixed to the vertical —2— of the batten, which supports a guide plate —10— which presses the arms —7—. As will be seen in Figure 2, this piece —10— forms a vertical plane but it has an angular recess —11— in the part opposite to the shuttle box —30— when the latter is in the working position so that the spring —6— of the box —30— presses, by its own elasticity, against the rear wall of the box and for this reason does not in the least hinder the in and out movement of the shuttle. While on the contrary, in the case of the other boxes of the mechanism the arm —7— is pushed by the guide plate —10— and the spring —6— is introduced into the interior of the shuttle box, taking the form shown in the plan, pressing against the shuttle —8— as is shown in Figure 1.

Due to the effect of the pressure of the spring —6— against the shuttle —8—, the latter becomes absolutely fixed in the interior of the box not being able to get displaced by the vibration and movements to which it is subjected during the working of the loom.

The guide plate —10— acts during the normal working of the loom as a fixed piece, but

it is convenient that the support —9— that holds it should be in the form shown in the plan or such other form as should be convenient to allow a certain elasticity in order to avoid breakdowns should the working of the boxes cease to be normal.

In order to avoid the vibration of the swell boxes, in the mechanism of this application, there has been applied to the upper part of the set of shuttle boxes —3— an arm —12— which is curved as is indicated in Figure 3 and which has a vertical arm —13— pointing downwards to come into contact with the extreme end of the box swells 5, the space between the two parts being relatively short, so that the oscillating of the box swells that are not working is limited by this vertical arm —13— the box swells being in this manner prevented from hindering the working of the mechanism.

As will be understood, it is not absolutely necessary that the retaining device be constituted by a spring of exactly the form shown in the drawing, but, on the other hand, its form can be varied always provided that it be an oscillating part which, by its elasticity, can permit the free movement of the shuttle, and when pressed by the guide plate —10— comes into position against the shuttle fixing 30 the same in the interior of the box.

I claim as the object of my patent:

1. In a drop-box loom having a box shuttle, and a shuttle box, a resilient regaining piece mounted on the rear end of the shuttle box, for holding an inactive shuttle in positively quiescent position in the shuttle box, a bent arm on the end of the retaining piece, a guide-plate mounted on the loom structure, adapted to hold the retaining piece 40 against the shuttle, and provided with an angular recess for releasing the retaining piece from the shuttle when the latter is brought into operatively active position.

2. In a drop-box loom, having a shuttle box and a plurality of box swells mounted on the latter, a spring retaining piece for each shuttle, mounted on the rear end of the shuttle box, each retaining piece having an aperture therethrough for the accommodation 50 of a box swell, an inwardly turned bent end on each retaining piece, a vertical guide-plate mounted on the loom, adapted to engage the turned ends of the retaining pieces, and hold the same against all the inoperative shuttles, said guide-plate being further provided with an angular recess for releasing the spring retaining piece of the shuttle which is in operative position in the shuttle box.

3. In a drop-box loom, having a shuttle box for holding a plurality of shuttles therein, a resilient retaining piece mounted on the shuttle box for each shuttle, a vertical guide-plate resiliently mounted on the loom structure, adapted to engage the ends of the re-

taining pieces and positively hold the inactive shuttles in the shuttle box, and means for releasing the end of the particular retaining piece holding the shuttle which is in operative position, for the purpose of freeing the latter from the grip of its resilient retaining piece.

4. In a drop-box loom a shuttle box for holding a number of shuttles, a spring retaining piece for each shuttle on the shuttle box, means for controlling the retaining pieces holding the inactive shuttles, and for releasing the particular shuttle which is in operative position, a resilient box swell for each shuttle mounted on the shuttle box, and an adjustable arm mounted on the top of the shuttle box, having a downwardly turned projection for limiting the vibrational travel of the box swells.

In testimony whereof he affixes his signature.
